UNITED STATES PATENT OFFICE.

SYLVESTER CUNNINGHAM, OF EVANSVILLE, INDIANA.

DETACHABLE HANDLE FOR BROOMS.

Application filed October 10, 1925. Serial No. 61,829.

This invention relates to detachable handles for brooms and has for its object the provision of a novel quick-attachable and detachable fastening, enabling the handle to be applied to the broom head or to be detached therefrom so that the user may retain the handle when the broom has become worn out and can attach the handle to a new broom head.

Another object of the invention is to enable the brooms to be shipped in knocked-down construction; the handles detached from the broom heads, thus minimizing the space required for shipment of a quantity of brooms.

The principal advantage of my invention over the old style of broom having a permanently attached handle is that the user only has to purchase a new broom head when the one in use becomes worn, instead of having to pay for a new handle each time a broom is purchased.

An embodiment of the invention is hereinafter described and is shown in the accompanying drawings in which—

Figure 1 is a side elevation, showing my improvements, the broom head being broken away;

Fig. 2 is a detail view taken at right angles to Fig. 1, showing the shell or tube in section to disclose the spring fastening;

Fig. 3 is a detail cross section through the shell or tube, spring, and cross-rod; and

Fig. 4 is a detail view of the tube and cross rod.

The broom head is shown at 1 and may be of the usual construction with a wire wound neck 2 and felt ring or band 3 but it is improved by the addition of a tube or shell 4 which extends down inside of the neck and into the broom head. The tube has an upper flange 5 which engages the upper end of the neck and also facilitates the entry into the tube of the detachable handle 6.

The detachable handle 6 is provided at its lower end with a cross slot 7 in which is located a spring 8 of peculiar shape, said spring being bowed at its upper end 9 and there fitting the curved end of the slot 7. The legs of the spring contract toward each other and consequently are arranged in con-

verging relationship. These legs have grooved parts 10 and they then continue as curved feet 11 which emerge from the slot 7 and engage the lower end of the handle 6.

The curved feet 11 engaging the lower end of the handle, are provided for the reason that they prevent vibration of the legs when the broom is in use and, they enable the legs to snap past the cross pin 12 without danger of catching on it until the grooved parts 10 encounter the cross pin.

The shell or tube 4 is provided with a cross pin or rod 12 which extends outwardly beyond the tube and into the broom head as shown in Fig. 1, thus anchoring the shell or tube in the broom head and preventing it from pulling out. The rod 12 also serves as a means to be engaged by the parts 10 of the spring 8 whereby the handle 6 is connected to the tube 4 as shown in Fig. 2.

Assuming that the broom head has been provided with the tube 4 and that the spring 8 has been located inside of the slot 7, the handle 6 is pressed down inside of the tube 4 until the parts 10 finally snap into engagement with the rod 12, said spring maintaining the connection. When it is desired to discard the broom head 1, a quick jerk on the handle 6 will cause the disconnection of the spring 8 from the rod 12, whereupon the handle may be withdrawn from the tube and reinserted in the tube of a fresh broom head.

What I claim is:

In a broom, the combination with a broom head, of a tube or shell located therein, a cross rod carried by the tube and which projects into the broom head to hold the tube in the said head, a handle detachably received within said tube and having a slotted lower end, and a doubled or rebent spring connector located within the slotted lower end aforesaid, said spring having parts adapted to engage the said rod and provided with lower parts which diverge and have their ends located below the lower end of the handle, for the purposes specified.

In testimony whereof I affix my signature.

SYLVESTER CUNNINGHAM.
